2 SHEETS—SHEET 2.

UNITED STATES PATENT OFFICE.

EUGENE B. COOKE AND CHAUNCEY O. LEWIS, OF NEW PHILADELPHIA, OHIO.

ADVERTISING WASTE-PAPER BOX.

1,108,066.

Specification of Letters Patent. Patented Aug. 18, 1914.

Application filed March 5, 1914. Serial No. 822,662.

To all whom it may concern:

Be it known that we, EUGENE B. COOKE and CHAUNCEY O. LEWIS, citizens of the United States, residing at New Philadelphia, in the county of Tuscarawas and State of Ohio, have invented certain new and useful Improvements in Advertising Waste-Paper Boxes; and we do declare the following to be a full, clear, and exact description of the invention, such as will enable others skilled in the art to which it appertains to make and use the same.

This invention relates to advertising boxes and more especially to waste paper boxes for use in stores, offices and on street corners or in other places.

The object of the invention is to provide a box of this character which is simple and durable in construction and which has removable advertising slides adapted to be readily inserted at will and which are suspended from the upper edge of the box.

Another object is to provide a box having a dome-like closure provided with a receiving aperture constructed for protection against the weather while remaining always open.

With these and other objects in view, the invention consists of certain novel features of construction, combination and arrangement of parts as will be more fully described and claimed.

In the accompanying drawings:—Figure 1 represents a perspective view of a waste paper box constructed in accordance with this invention taken from one of the rear corners and showing the receiving opening; Fig. 2 is a central vertical section thereof; Fig. 3 is a horizontal section taken on the line 3—3 of Fig. 2; Fig. 4 is a perspective view of the upper portion of the box with the lid in open position and the bag removed; Fig. 5 is a detail plan view of the box top with the top open.

In the embodiment illustrated, a skeleton frame 1 is shown comprising a base or bottom 2 having angular upright strips 3 secured thereto the upper ends of which are connected with a band 4 forming the top of the frame. This band 4 is provided at its upper edge with an inturned flange 5 and said band is here shown in rectangular form having triangular corner plates 6 at each corner which are designed to brace the frame and render it rigid. Each of these plates 6 has an upwardly projecting stud 7 for a

purpose to be described. As shown, this band 4 has an inturned flange 8 also at its bottom or lower edge but this may be dispensed with if desired it being provided only for the purpose of strengthening the band. The bottom 2 is shown provided with down-turned right-angular flanges 9 which strengthen said bottom and also provide additional attaching means for the outer angular guide strips to be described. Outer angular strips 10 are disposed over the strips 3 and have arranged between them intermediate similarly shaped spacing strips 11, said spacing strips being of less width than the strips 10 so that when the parts are assembled the edges of said spacing strips will be spaced inwardly from the edges of the outer strips 10 to provide suitable guides when the parts are assembled for the removable advertising slides to be described. The transversely angular outer strips 10 have their lower ends extended below the bottom 2 to form supporting legs for the box which may be of any desired length. The spacing strips extend from the upper end of the outer strips 10 which are arranged flush with the top edge of the band 4 to a point opposite the free edges of the flanges 9 on the bottom 2 of the frame and these strips may be secured together by any suitable means riveting or soldering being usually employed. It will thus be obvious that when these inner, outer and intermediate strips are assembled, the free edges of the inner strips 3 and of the outer strips 10 will be spaced apart a distance equal to the thickness of the strips 11 and suitable guides thus provided for the removable advertising slides which form the side members of the box. As shown the inner strips 3 are of greater width than the outer strips 10 and project slightly beyond the edges thereof but this is not necessary but is desirable as it forms a more effective guide.

The rear wall of the casing or box is formed by a plate 12 which is of a width slightly less than the distance between the free edges of two of the intermediate strips 11 arranged at opposite corners of the frame 1 and this plate is adapted to be inserted in the guides formed by the inner and outer strips 3 and 10 which form the two rear standards or supports of the frame. This plate 12 is provided at its upper end with an inturned flange 13 which is adapted to extend over and engage the flange 5 on the

band 4 at the rear side of the frame and to be secured thereto in any suitable manner. The lower edge of this plate 12 has an upturned flange 14 on its lower edge between which and the inner face of the plate 12 one of the flanges of the bottom 2 is designed to fit and to be secured by riveting or otherwise. This rear plate 12 is permanently attached to the frame 1 and is designed to support a hinged closure hereinafter described.

The sides and front wall of the box are formed by removable slides 15 all of which are exactly alike and consequently one only will be described in detail. Each slide 15 is composed of sheet metal or any other suitable material and of a width substantially equal to the distance between the free edges of two of the spacing strips 11 arranged at opposite corners of the frame and between which the edges of said slides are adapted to move, the inner and outer faces of the side edges of said slides being guided by the free edges of the inner and outer strips 3 and 10 at the ends of the frame. The upper end of each slide 15 has an inturned right-angular flange 16 extending from one side edge to the other forming a lip which is adapted when the slides are in operative position to rest on the flange 5 at the upper edge of the band 4 and thus support the slide and limit its downward movement. The lower edge of the slide is provided with a spacing or guiding strip 17 here shown in the form of a flange turned upwardly and folded flat against the outer face of the slide and having its opposite ends cut away a sufficient distance to permit the side edges of the slide to move freely in the guides of the frame, said strip or flange 17 being of a length equal to the distance between the free edges of two of the outer strips 16 arranged at opposite corners of the frame.

The closure 20 for this box is substantially dome-shaped in form and is hinged at one edge to the rear plate 12 of the frame near its upper end. This top or closure 20 as shown is constructed of a band 21 slightly larger than the band 4 of the frame to adapt it to fit down over said band 4 when closed and it is provided on its inner face with a laterally extending flange 22 spaced a suitable distance from its lower edge to form a stop for limiting the closing movement of the top, said flange 22 resting on the flange 5 of the frame when the top is in closed position. On this band 21 is an upwardly converging roof 23 the lower edges of which project beyond and overhang the band 21 to form protection for the inlet or receiving opening 24 which is formed in the rear wall of the band 21. A shelf or plate 25 is secured within said closure 20 adjacent the lower edge of the opening 24,

said opening being preferably rectangular in form as shown. This plate 25 is inclined upwardly and inwardly to prevent rain or snow from entering the box, said inclination of the plate causing it to shed water and to prevent its passage into the interior of the box. The free edge of this plate 25 is preferably provided with a downturned flange 26 to which one end of a chain or other flexible element 27 may be secured, the other end of said chain being secured to one of the corner plates 6 at the rear of the frame and is designed to limit the opening movement of the top 20.

Apertured lugs 28 and 29 are secured respectively at one corner of the frame and to the corresponding corner of the top in position to cause the apertures thereof to register when the top is in closed position and to bring said lugs in close proximity to receive a suitable lock for fastening the top to the box.

The parts of this box are preferably composed of galvanized iron but they may be composed of any desired material and the slides while shown in metal may be made of glass or other material desired.

A removable lining or bag 30 is adapted to be inserted within the box and is shaped to correspond to the shape of the box, both being here shown rectangular in cross section. This bag is preferably provided at its upper edge on its four corners with eyes 31 which are adapted to be engaged with the studs 7 on the corner plates 6 which hold the bag in upright position ready to receive waste paper and other refuse and prevent the top thereof from being forced downwardly and exposing the side walls of the box to contamination. This bag may be constructed of any desired material, heavy paper being preferably employed so that it may be removed and destroyed when necessary.

The slides 15 which may be readily removed and changed when desired are provided on their outer faces with suitable advertising matter which renders them especially useful to merchants as they may change the slides to meet the requirements of their business for instance, to advertise special sales, Christmas goods and the like. Should the merchant owning the cans sell out his business the cans may be used afterward by his successor by simply changing the slides.

We claim as our invention—

1. In an advertising waste paper box the combination of a skeleton frame comprising a bottom, angular upright strips secured to said bottom, a top band connected to said strips and having an inturned flange at its upper edge, guides at the opposite edges of said strips, removable advertising slides engaging said guides and forming the side

walls of the box each having an inturned lip at its upper end for engaging the flanged upper end of said top band to limit the downward movement of said slide, and a 5 hinged closure for said box.

2. In an advertising waste paper box the combination of a skeleton frame comprising a bottom, angular upright strips secured to said bottom, a top band connected to said 10 strips and having an inturned flange at its upper edge, guides at the opposite edges of said strips, removable advertising slides engaging said guides and forming the side walls of the box each having an inturned lip 15 at its upper end for engaging the flanged upper end of said top band to limit the downward movement of said slide, the lower edge of said slide having a guide strip on its outer face terminating at its opposite 20 ends at points spaced from the side edges of said slide.

3. In an advertising waste paper box the combination of a skeleton frame comprising a bottom, angular upright strips secured to 25 said bottom, a top band connected to said strips and having an inturned flange at its upper edge, guides at the opposite edges of

said strips, removable advertising slides engaging said guides and forming the side walls of the box, each having an inturned 30 lip at its upper end for engaging the flanged upper end of said top band to limit the downward movement of said slide, the lower edge of said slide having an upturned flange on its outer face with its ends cut 35 away adjacent the side edges of said slide, and a closure for said box.

4. A waste paper box having a top hinged to the upper end thereof and shaped to fit over said upper end, a stop on the inner 40 face of said top to limit its closing movement, said top having an opening in one side wall, a plate in said top secured to the lower edge of said opening and extending upwardly and inwardly, and a member 45 overhanging said opening.

In testimony whereof we have hereunto set our hands in presence of two subscribing witnesses.
